ROLLIN C. LEWIS, OF STAMFORD, CONNECTICUT, ASSIGNOR TO THE YALE & TOWNE MANUFACTURING COMPANY, OF STAMFORD, CONNECTICUT.

RELEASING-SLIDE FOR COMBINATION-LOCKS.

1,166,232.

Specification of Letters Patent. Patented Dec. 28, 1915.

Application filed September 15, 1915. Serial No. 50,824.

To all whom it may concern:

Be it known that I, ROLLIN C. LEWIS, a citizen of the United States, and a resident of Stamford, in the county of Fairfield 5 and State of Connecticut, have invented certain new and useful Improvements in Releasing-Slides for Combination-Locks; and I do hereby declare the following to be a full, clear, and exact description of the invention, such as will enable others skilled 10 in the art to which it appertains to make and use the same.

My invention relates to an improvement in combination locks, the object being to 15 provide means operable from the outer side of the lock casing for disconnecting and connecting the driving tumbler center and the tumbler, whereby the tumbler center may be disconnected and turned without 20 turning the tumbler, thus changing the combination, and then restored to its normal operative position within the tumbler.

A further object is to provide the lock casing with a tumbler setting sight hole, 25 whereby the movement of the tumblers can be observed, the said sight hole having a transparent cover to exclude dust.

A further object is to provide improved 30 means for attaching the knob spindle to the dial knob and ring, so that it may be used on doors of various thicknesses, within cer- 35 tain limits, without changing any of the parts.

In the accompanying drawings, Figure 1 35 is a view in elevation of a lock embodying my invention showing the tumbler shifting slide in its normal position; Fig. 2 is a similar view showing the slide in its shifted position; Fig. 3 is a view in section of the 40 lock and dial, the slide being in the position shown in Fig. 1; Fig. 4 is a similar view with the slide in the position shown in Fig. 2; Fig. 5 is a view of the lock casing showing the tumbler setting sight hole; Fig. 6 45 is a view in section through the face plate of the casing showing the transparent cover for the sight hole; Figs. 7, 8 and 9, show the dial spindle and washer, and the method of securing the washer to the spindle; Fig. 10 50 is a view of the driving tumbler and Fig. 11 a view of the driving tumbler hub and tumbler center.

1 represents the lock casing, 2 a series of tumblers therein and 3 is the driving tum-

bler or the tumbler to which motion is 55 directly imparted by the dial spindle, and which by its rotation, rotates the other tumblers 2 in the well known manner. The tumblers 2 are mounted to rotate on a suitable support within the lock casing, and the driving tumbler 3 is also mounted on said support and is provided with a central section 5 having a hub 4, which in the present instance projects through one face of the lock case. The hub 4 carries the driving 60 tumbler center 5, which is disk shape and provided at its periphery with teeth which mesh with similarly shaped teeth formed in the margin or wall of the recess in the driving tumbler, in which said tumbler center 5 normally rests, so that when tumbler center is in its normal position and locked to the tumbler 3, the two parts will rotate 65 together and rotate the other tumblers 2 in the well known manner. This hub 4 and 70 the tumbler center 5 carried thereby, are free to be moved lengthwise the hub, so that when moved in one direction the tumbler center 5 will be disconnected from its tumbler 3, and when moved in the other direc- 75 tion will engage and mesh with the teeth on said tumbler, so that when the hub 4 is rotated, the tumbler 3 will be rotated with the same. The hub 4 is provided with an angular opening through the same for the 80 reception of the angular spindle 6, and the support carrying the tumblers 2 is also made hollow so that the said spindle may rest 85 therein, the bore of the support being of greater diameter than the spindle so that 90 there will not be any contact between the parts. By this arrangement, the spindle 6 may be of a length to fit any thickness of door within certain limits and be applied 95 to the door without any cutting or adjust- ing of the parts.

The hub 4 is provided with a peripheral 100 groove 7, in which the cams 8 on the slide 9 rest and move. This slide is provided with an elongated opening 10, which is en- 105 larged at one end to permit the hub 4 to be passed through the same, and is narrowed at its other end, the side walls of the narrowed part being cam shaped, or inclined, so that when the said slide 9 is pulled down- 110 wardly the cams thereon, acting against the shoulders or wall of the groove in the hub, shifts the latter endwise and withdraws the

tumbler center 5 from its tumbler 3, thus leaving the center free to be turned by the dial knob without turning the tumbler, and when the slide is shifted to its other position, it forces the tumbler center into its seat in the tumbler thus locking the two parts together. This slide 9 is slotted as at 11 to receive the post 12 which assists in guiding the latter and the end of the slide 10 projects through the lock case and is preferably bent as at 13 to permit it to be readily grasped and operated from the outside of the lock case.

The spindle 6 is provided near its outer 15 end with a circular groove 14^a in which the washer 14 is slipped and partly turned, after which it is permanently secured on the spindle, by upsetting the metal of the spindle in one or more of the corners of the square hole 20 in the washer. This washer rests against the rear face of the dial ring 15 and the spindle is locked to the dial ring by the knob shank 16, which bears against the front face of the dial ring, and by the screw 17, screwed into the end of the spindle with its head 25 overlapping the outer end of the shank. The dial 18 is carried by the shank 16 and is secured thereto by the dial knob 19 screwed onto the shank.

30 In applying the dial to a door, the screw cap 20 in the end of the knob 19, and the screw 17 in the end of the spindle are removed. This leaves the knob shank and its attached knob and free dial to be removed, 35 from the spindle. The dial ring with the spindle in position therein, is secured to the door by screws 21 after which the knob shank, with its knob and dial thereon, is placed on the end of the spindle and secured 40 by the screw 17 and the latter concealed by screwing on the cap 20. The spindle projects through the door and through the angular hub of driving tumbler and projects more or less, according to the thickness of 45 the door, into the support carrying the tumblers 2.

A sight hole is provided in the lock case so as to permit the operator to view the movements of the tumblers and fence and is 50 preferably covered by a transparent cover 22, which in the present instance rests on a seat in the lock case and the metal of the latter spun over the edge of the cover to retain it in position. Other means of securing 55 it in position may however be substituted.

In order to change the combination of the lock, the safe, vault, or other door is opened thus giving access to the lock case 1, at the rear of the door. The slide 9 is then pulled 60 downwardly during which movement the cams 8 on the slide moves the tumbler center out of engagement with the driving tumbler, thus leaving former free to turn without rotating the latter, and in condition for 65 changing the combination, which is accom-

plished by turning the dial to bring the desired number on the dial in line with the setting mark, and pushing up the slide which latter movement forces the driving tumbler center into engagement with the driving 70 tumbler. During this operation, the operator may view the movement of the tumbler and fence through the sight hole in the lock case.

It is evident that many slight changes 75 might be resorted to in the relative arrangement of parts shown and described without departing from the spirit and scope of my invention. Hence I would have it understood that I do not wish to confine myself 80 to the exact construction and arrangement of parts shown and described but

Having fully described my invention what I claim as new and desire to secure by Letters-Patent, is:—

85 1. In a combination lock, the combination of a plurality of tumblers one of which is the driving tumbler, a slideable and rotary hub, a slide located within the lock casing and forming a permanent part of the lock 90 and operable from the outside of the casing, the said slide having means to engage the hub for moving the latter endwise to disconnect it from and connect it to the driving tumblers, and a spindle for rotating the hub. 95

2. In a combination lock, the combination of a plurality of tumblers, one of which is the driving tumbler, a slideable and rotary hub having peripheral shoulders, a slide operable from the outside of the lock case and 100 having a cam to engage said shoulders for moving the hub endwise to disconnect it from and connect it to the driving tumblers and a spindle for rotating the hub.

3. In a combination lock, the combination 105 of a plurality of tumblers one of which is the driving tumbler, a slideable and rotary hub having teeth to engage teeth on the driving tumbler and also provided with peripheral shoulders, a slide operable from the outside of the lock case and having a cam to engage said shoulders for moving the hub endwise to disconnect it from and connect it to the driving tumbler and a spindle for rotating the hub. 110

115 4. In a combination lock, the combination of a lock case, a plurality of tumblers one of which is the driving tumbler composed of a tumbler proper and a central member having a hub, the said central member being provided with teeth to engage teeth on the tumbler proper, and the hub having peripheral shoulders, a slide within the lock and projecting at one end from the latter, the said slide having a cam to engage the shoulders on the hub for shifting the latter longitudinally, and a spindle for rotating the driving tumbler. 120

125 5. In a combination lock, the combination of a dial ring, a spindle, a washer rigidly 130

secured to the spindle and bearing against the rear face of the ring, a knob and a dial detachably secured to said spindle in front of the ring and tumblers one of which is a driving tumbler, having a hub with an angular bore to receive the spindle.

In testimony whereof, I have signed this

specification in the presence of two subscribing witnesses.

ROLLIN C. LEWIS.
